UNITED STATES PATENT OFFICE.

WILLIAM E. GUESE, OF TOLEDO, OHIO, ASSIGNOR OF ONE-HALF TO GEORGE A. FOX, OF TOLEDO, OHIO.

BILLIARD-CUE CHALKER.

SPECIFICATION forming part of Letters Patent No. 737,226, dated August 25, 1903.

Application filed October 23, 1902. Serial No. 128,373. (No model.)

To all whom it may concern:

Be it known that I, WILLIAM E. GUESE, a citizen of the United States, residing at Toledo, in the county of Lucas and State of Ohio, have invented certain new and useful Improvements in Billiard-Cue Chalkers; and I do hereby declare the following to be a full, clear, and exact description of the invention, such as will enable others skilled in the art to which it appertains to make and use the same.

My invention relates to devices for chalking cues used in playing the game of billiards, pool, and the like; and the primary object thereof is to provide a compact, inexpensive, and highly efficient article of pleasing appearance.

A further object is to provide such an article which will possess special advantages as a hand-operated device.

To this end the invention includes the combination and arrangement of component parts and details of construction to be hereinafter described, and particularly pointed out in the claims.

While the invention is susceptible of some modification, the accompanying drawings show and I shall hereinafter describe in connection therewith what is now conceived to be the preferred embodiment of the same.

The invention is illustrated in the accompanying drawings, in which—

Figure 1 shows the article in perspective and the manner of using the same. Fig. 2 is a longitudinal sectional view, parts being shown in elevation; and Fig. 3 is a detail end view of the chalk-cup.

My invention includes generally a sheet-metal barrel closed at one end, having spiral guides formed in the periphery thereof which open out through the opposite end of the same, a chalk-cup designed to be inserted into the barrel through the latter end and provided with peripherally-arranged projections engaging the guides in the barrel, whereby the cup will be rotated as the former is reciprocated in relation thereto, a spring interposed between the closed end of the barrel and the cup, and a cap detachably secured to the end of the barrel, through which the cup is inserted, having a cue-opening disposed axially of the same and portions to coact with the chalk-cup to prevent the

latter being ejected from the barrel by the spring. The barrel is designated in the accompanying drawings by the numeral 1, is 55 provided with a plurality of peripherally-arranged spiral guides 2, running longitudinally thereof and extending entirely to and through the edge of one end *a* of the same. In the particular exemplification of my invention disclosed herein these guides are formed by convex grooves pressed out of the body of the barrel, and they run the full length of the latter and open out through both ends of the same. One end of the barrel is closed by a cap 3, which, while it is shown as detachable and such construction possesses special advantages, as will be hereinafter described, may be permanently secured in place.

The chalk is carried by a cup 7, fitted to the bore of the barrel and provided with peripheral projections 9 for engagement with the grooves 2. This cup is preferably formed by a casting having a recess 8 in the same of 75 the shape of the exterior configuration of the block of chalk to be held therein, which block fits the recess snugly, so that it will be retained in place by frictional contact, and upon the periphery of the cup a plurality of spirally-arranged ribs are located, extending from end to end of the same, which constitute 80 the projections 9, before described. The cup is inserted into the barrel through the end *a* thereof, and between the former and the cap 85 3 a helical spring 10 is interposed, which is housed within the barrel and which tends to force the cup toward the end *a* of the latter and to eject said cup when the end referred to is unobstructed. To normally retain the 90 cup within the barrel and at the same time provide a guide for the cue in the chalking operation, a cap 5 is provided, which is detachably secured to the end *a*, has an axially-arranged opening 6, forming a cue-guide, and 95 is provided with an intact portion which coacts with the cup to prevent the ejection of the same under the influence of the spring 10. The cap 5 is detachably mounted upon the end *a*, so that it may be displaced to remove 100 the cup in order to replenish the chalk.

In order to facilitate the manufacture of the device, and particularly the assemblage of the parts thereof, the ends of the barrel

are duplicates of each other, so that the cap 3 may be secured to either end, the cup inserted into the barrel through the opposite end, and the cap 5 secured to the latter with 5 equal facility.

The means for securing the detachable engagement described between the end of the barrel and the cap preferably consists of interengaging screw-threaded parts, and in order to adapt the ends of the barrel to carry even threads and also for the purpose of reinforcing the barrel to prevent separation of the longitudinal meeting edges thereof a cast-metal ring 1' is fitted peripherally of the barrel at the extremity of each end of the same.

In using the article the same is gripped in one hand and the cue in the other, with the butt of the latter resting upon the floor. The end of the cue is inserted through the opening 6, and then the device is given a few reciprocations. As the chalk bears directly upon the tip of the cue, it will be prevented from partaking of the reciprocatory movement of the barrel, but will be given a rotary 25 movement as the latter reciprocates in relation thereto, so that the tip of the cue will be efficiently chalked.

In order that the article may be suspended in a convenient position, a stud 4, secured to 30 the end of the cap 3, axially of the same, is provided, which has an opening extending through the same for the reception of a ring or other attaching device.

The construction and operation of my invention will be readily understood upon reference to the foregoing description and accompanying drawings, and it will be appreciated that the parts and combinations recited may be varied within a wide range without departing from the spirit and scope thereof.

Having described my invention, what I claim, and desire to secure by Letters Patent, is—

45 1. In a hand implement for chalking a cue and in combination, a tubular barrel closed at one end and having spiral grooves formed in the periphery thereof extending entirely to and through the edge of the opposite end 50 of the same, a chalk-cup designed to be inserted into and removed from the barrel through the latter end, integral projections disposed peripherally of the cup engaging the

spiral grooves, a spring interposed between the rear end of the cup and the closed end of 55 the barrel, and a cap removably secured to the opposite end of the barrel having a portion coacting with the cup when the latter is in the barrel to prevent the ejectment thereof by the spring, said cap also having an opening 60 for the cue, substantially as described.

2. In an implement for chalking a cue and in combination, a sheet-metal barrel having corresponding cap-engaging means at each end thereof, and spiral grooves pressed out of 65 the periphery thereof, running from end to end of the same and opening out through one of its end edges, a cap secured to the opposite end of the barrel for closing the same, a cast-metal cup designed to be inserted into 70 and removed from the barrel through the first-mentioned end thereof, said cup having peripherally - arranged integral ribs for engagement with said grooves, a spring interposed between said cup and said cap, and a 75 second cap removably secured to said first-mentioned end of the barrel, said second cap having a cue-opening and means to coat with the cup to retain the same in the barrel when said second cap is in place, substantially as 80 described.

3. In an implement for chalking a cue and in combination, a sheet-metal barrel having corresponding cap-engaging means at each end thereof and spiral grooves pressed out of 85 the periphery thereof running from end to end of the same and opening out through both of its end edges, a cap secured to one of 90 said end edges for closing the same, a cast-metal cup designed to be inserted into and removed from the barrel through the opposite end thereof, said cup having peripherally-arranged integral spiral ribs engaging said 95 grooves, a spring interposed between the cup and said cap, and a second cap removably secured to the end of the barrel through which the cup is inserted and removed, said second cap having a cue-opening and means for engaging the cup to retain the same in the barrel, substantially as described. 100

In testimony whereof I hereunto affix my signature in presence of two witnesses.

WM. E. GUESE.
